UNITED STATES PATENT OFFICE

CHARLES A. AHLSTROM, OF JAMESTOWN, NEW YORK.

MUSIC-SHEET FOR MANUALLY AND MECHANICALLY OPERATED MUSICAL INSTRUMENTS.

1,122,237.

Specification of Letters Patent. Patented Dec. 22, 1914.

Application filed December 19, 1912. Serial No. 737,589.

To all whom it may concern:

Be it known that I, CHARLES A. AHLSTROM, a citizen of the United States, residing at the city of Jamestown, in the 5 county of Chautauqua and State of New York, have invented certain new and useful Improvements in Music-Sheets for Manually and Mechanically Operated Musical Instruments, of which the following, taken 10 in connection with the accompanying drawings, is a specification.

The invention relates to perforated music sheets for player pianos and other mechanically actuated musical instruments, and the 15 object of the improvement is to provide a novel yet simple manner of perforation of the music sheet by which the melody notes or other notes which it is desired to accentuate are distinctly marked by mixed styles of 20 perforations in each melody note; and the invention consists in the manner of perforating the music sheet as shown in this specification and the accompanying drawing and pointed out in the claims.

25 In the drawing a plan view of a portion of the music sheet of a player piano is shown in position upon the tracker bar, showing my manner of perforation of the music sheet in order to indicate the notes 30 to be accented.

The numeral 1 designates the tracker bar which has the series of air holes 2 extending therethrough in the usual manner.

The numeral 3 designates the music sheet 35 in which the perforations for the different notes consist of one or more round openings, which are designated by the numeral 4. This manner of perforating the music sheets so as to coincide with the air holes 2 40 of the tracker bar is highly preferable since the perforations 4 may be placed a slight distance apart without interfering with the continuation of the musical tone or rendering of the composition, and yet allowing a 45 connection of the music sheet between the holes, which forms a strengthening bridge therebetween, thus greatly strengthening and prolonging the life of the music sheet.

In order to give the best rendering of the 50 musical composition it is necessary for the performer to have the notes which carry the melody of the composition plainly indicated so that there can be no mistake as to their arrangement so that the eye will 55 automatically perceive said arrangement

and the performer can musically phrase or accent the different parts as the sheet progresses over the tracker bar.

My manner of indicating the melody notes or other notes which it is desired to accent 60 is to punch or otherwise perforate the first three or four openings or holes of a series of the perforations 4 of the music sheet in a continuous slot, which slot is designated by the numeral 5. In the case of a short note 65 with four perforations or less than that number, the entire note is formed in a slot and is designated by the numeral 6. Special notes 7 may be accented in the accompaniment in the same manner as shown in the 70 melody. The plainness of this simple method of indicating the melody notes or other notes to be accented is clearly shown in the drawing, which drawing is a reproduction of a portion of the piano solo the 75 "Traumerei", by Schumann, and the melody notes are made perfectly plain at a glance so that an exceedingly accurate rendering may be easily attained by the performer on the instrument. It is obvious 80 that this method of indicating the accented notes or melody is very simple and easy of attainment in the manufacture of the music sheet, since it consists in simply prolonging the opening 4 for the required number of 85 holes, which is preferably four in notes of that length; the uniformity in the length of the slots 5 or 7 aiding in readily distinguishing the notes to be accented.

I claim as new—

1. A music sheet for manually and mechanically operated musical instruments having a series of equal size perforations with bridging therebetween for each of the notes except those which are to be accented, 95 and the accent notes having a short slot of the same width as said equal size perforations and at the beginning of said series of said perforations in said accent notes.

2. A perforated music sheet for manually and mechanically operated musical instruments having a series of round perforations of the same size and equally spaced for the unaccented notes, said perforations having an equal length short slot at the beginning 105 of each series for each melody note where the length of said series will permit.

3. A perforated music sheet for manually and mechanically operated musical instruments having a series of equal size and 110

equally spaced perforations for the unaccented notes with a connection of the music sheet between said perforations, and the perforations for the accented notes having a slot at the beginning of each of series of a length of four of said perforations except in shorter notes than said four perforations which shorter notes have a continuous slot.

4. A music sheet comprising, in combination, a series of bridged perforations for each of a plurality of accompaniment notes;

and a series of bridged perforations for each of a plurality of theme notes, each said theme series having a theme distinguishing perforation of different appearance from perforations of the accompaniment series. 15

In testimony whereof I have affixed my signature in the presence of two witnesses.

CHARLES A. AHLSTROM.
